EXTENSIBLE DESK TOP

James R. Clark, Rochester, N. Y., assignor to
 Yawman & Erbe Mfg. Co., Rochester, N. Y., a
 corporation of New York

Application November 7, 1928, Serial No. 317,864

10 Claims. (Cl. 45—6)

This invention relates to an extensible top for furniture construction and it pertains more particularly to a commercial bookkeeper's desk adapted to be used with a bookkeeping machine 5 and a portable posting tray so that the bookkeeper may expeditiously make entries, consult various card indexes, etc. with comfort and convenience.

In modern bookkeeping practice it is desirable 10 to provide a bookkeeper with a complete "plant" in which the desk must preferably be compact and relatively small.

An object of this invention is to provide such a desk with an extensible top whereby adequate 15 space may be provided for sorting checks, bills and other papers, examining large and bulky ledgers, etc.

A further object is to provide an extensible top in which the entire top surface is in a single 20 plane when it is in an extended position.

A further object is to provide an extensible top in which a portion of the structure serves as a back for the desk when said top is in closed position.

25 Another object is to provide a desk of this type with a telescoping guard rail which serves to prevent the front of the extending top from tipping forward.

Other objects will be apparent as the detail 30 description of my invention proceeds.

In the accompanying drawings, wherein similar parts are represented by like reference characters throughout the several views,

Figure 1 is a perspective of my improved book- 35 keeper's desk showing the top in closed position with the pivoted portion forming a back for the desk and showing the relative position of the bookkeeping machine;

Figure 2 is a similar perspective showing the 40 desk top in extended position with the back folded down to form a part of the top;

Figure 3 is a longitudinal sectional view through 45 my improved desk top showing the structural details of a preferred form taken generally on the line 3—3 of Fig. 2;

Figure 4 is a similar view of the section shown in Fig. 3 but with the desk in closed position;

Figure 5 is a section taken along the lines 5—5 50 of Figure 3 with some of the details omitted for clarity;

Figure 6 is a horizontal section of a second embodiment of my invention; and

Figure 7 is a similar section with the desk in closed position.

55 Referring to Figures 1 and 2, a desk 10 is pro-

vided with simple drawers 11 and a slidable top 12. This top is preferably provided with an extension 13 for utilizing the space between the desk and the bookkeeping machine 14, a cut-away portion 15 being provided to allow the carriage 60 16 of the bookkeeping machine to travel therein. A pivoted member 17 serves as a back for this desk in closed position (see Fig. 1) and is adapted to turn into the plane of the desk top to form a continuous top surface therefor in extended position (see Fig. 2).

The desk is provided with end guard rails 18 and 19 and with a rear guard rail 20. The end guard rails are provided with offset rebent flanges 21 and 22 which form a guide for receiving the 70 guard rails 23 and 24 on the slidable top member 12. Guard rail 24 is connected with a guard rail 25 extending across the rear of projection 13. The function of the guard rails is to prevent papers, checks or cards from being blown or pushed 75 off the desk and a further function of said guard rails is to provide a reenforcement and to prevent the front of the extended portion from tipping downwardly when a heavy object is placed thereon.

In Figures 3, 4, and 5 I have shown an embodiment of my invention in which the pivoted top is not positively connected with the slidable top. This modification may be mounted directly on the top of a desk or it may be mounted on an 85 auxiliary top 26 provided with a front rebent flange 27 for providing reenforcement and simulating thickness, and with a rear flange 28 adapted to be secured to the rear guard rail 20.

A lateral flange 29 secured to auxiliary top 26 90 may be employed for securing this auxiliary top to an existing article of furniture, apertures 30 being provided in this flange for suitable rivets or screws.

A hinge 31 is secured to the rear guard rail 20 95 and to the pivoted top member 17 by hinge leaves 32 and 33 respectively.

The pivoted top member 17 may be formed by bending a sheet of metal as shown in Figure 4; starting with flange 35 the sheet is bent to form 100 an end 36, a top 37, and another end 38. The bottom 39, is a separate element fitting under the flange 35 to form a closed rectangular section. The top is preferably provided with a suitable covering 40 such as linoleum, the ends carrying 105 metallic strips 41 and 42 for protecting the exposed edges of the top material 40.

The slidable top portion consists of a metal plate 43 having a front rebent flange 44 to reenforce it and to simulate thickness. The rear part 110

of sheet 43 consists of a downwardly extending flange 45 terminating in a rearwardly extending flange 46. The rearwardly extending portion serves as a guide and stop member for positioning the pivoted top member 17 in alinement with the slidable top member 12. The slidable top member is also provided with a suitable covering material 47 such as linoleum, the edges of said material being protected by suitable binding strips 10 48 and 49.

Between the slidable top portion and the auxiliary top 26 I provide a suitable roller suspension means 50. This may consist of front rollers 51, rear rollers 52 mounted on shafts 53 held in spaced position by bars 54, the whole assembly 15 acting as a truck to support the slidable top and to provide a substantially frictionless sliding suspension means therefor. The outward movement of this slidable suspension means is limited by stop member 55 secured to auxiliary top 26 and its inner movement is limited by stop member 56. The rear portion of stop member 56 is provided 20 with an offset flange 57 adapted to co-act with a flange 58 carried by the slidable top to limit the outer movement of the top and to prevent the extended portion from tipping downwardly.

In Figures 6 and 7 I have shown an embodiment in which the pivoted top portion is in two sections, one of which is pivotally mounted to the 30 slidable portion. The auxiliary top 26 with the guard rails 18, 19, 20, etc. are the same as have been already described. In this modification, however, the edges of the metal strips 59 and 61 are rolled to form a part of hinges 31, 60 and 62 respectively, hinge 31 being secured to rear guard rail 20 as by welding and hinge 62 being secured to slidable top 12 by hinge leaf 63. Any conventional slidable mounting means may be employed 35 to reduce friction or if desired the slidable top may slide directly on the auxiliary top 26.

The operation of the device as above described is obvious. When the pivoted member 17 of Figures 3 to 5 is in its upper position and the slid- 40 able member 12 is closed, leaf 33 on end 38, rests on the top surface of the slidable portion to hold the pivoted portion 17 firmly in its upper position whereby it may serve as a fixed back to the desk. As the slidable portion is extended, the rebent flanges 21 and 22 hold guard rails 23 and 24 and prevent a weight on the front part of the slidable top from tipping it downwardly. When the slid- 45 able portion is in its extreme position flange 58 fits snugly under flange 57, stopping this member so that it will register with the pivoted top 17, the latter being alined by the rearwardly extending flange 46 on the slidable portion. The operation of the device illustrated in Figures 6 and 7 is similar to that above described, except that no stop or guide means are necessary. In the closed 50 position hinge 62 contacts with hinge 31 so that plates 59 and 61 extend vertically against rear guard rail 20 to form a back for the desk. When the top is extended this back is automatically converted into top surface to increase the effective area of the desk top. The telescoping guard rails perform the same function as in the other 55 modification.

While I have described preferred embodiments of my invention it is understood that I am not limited to the details set forth, except as defined by the appended claims.

I claim:

1. In combination with a commercial book-keeper's desk, an auxiliary top member, a slid- 70 able top member, means for slidably mounting

said sliding top on said auxiliary top, means for limiting movement of said sliding top in both directions, a guard rail fixed to said auxiliary top, a pivoted top member hinged to said guard rail to swing upwardly above the surface of the 80 desk whereby said pivoted top is alined with said slidable top in extended position and whereby it is supported in a vertical position by said slid- 85 able top when closed.

2. A desk of the type described comprising a 85 body, an auxiliary top, a forwardly slidable top mounted thereon, foldable top means between the rearward edge of the slidable top and the rearward edge of the body for rearwardly ex- 90 tends the surface of the slidable top along sub- stantially the plane thereof when the top is in its forward position, said foldable top comprising a plurality of hinged leaves rigidly support- 95 ed by said auxiliary top when extended, the forward edge of the forward leaf being hinged to the rearward edge of the slidable top, and the rearward edge of the rearward leaf being hinged to the rearward edge of the body whereby, when said slidable top is in its rearward position, the leaves are folded upwardly into substantially ver- 100 tical position.

3. A desk of the type described comprising a body, a forwardly slidable top mounted thereon, foldable top means between the rearward edge of the slidable top and the rearward edge of the 105 body for rearwardly extending the surface of the slidable top along substantially the plane there- 110 of when the top is in its forward position, said foldable top comprising a plurality of hinged leaves, the forward edge of the forward leaf be- 115 ing hinged to the rearward edge of the slidable top, and the rearward edge of the rearward leaf being hinged to the rearward edge of the body whereby, when said slidable top is in its rearward position, the leaves are folded upwardly into sub- 120 stantially vertical position, and an upstanding wall extending across the back edge of the body, said leaves being of substantially the height of the back wall whereby, when they are folded to their upward position, the leaves lie adjacent and sub- 125 stantially parallel with the back wall and extend upwardly to approximately the height of the back wall.

4. In a desk of the class described, a top there- 125 for comprising a frame adapted to be secured at the upper extremity thereof, a sheet metal strip upstanding from said frame for providing a guard rail for the surface of said desk, a top member mounted on said frame to provide a normal area of working surface on said desk 130 and being adapted to slide forwardly and rearwardly on said frame, a second top member pivotally secured at the corner formed by the junction of the said guard rail with the said frame and adapted to swing upwardly above 135 the working surface of the desk, said pivoted top member being adjustable for providing an additional area of working surface on said desk in the same plane as said slidable top member when- 140 ever the same is in its forward position, and means providing a stop for limiting the forward movement of said slidable top member at that position just sufficient to provide a space to accommodate said pivoted top member so that a continuous enlarged area of working surface may 145 be provided on said desk.

5. In a desk of the class described, a top sur- 145 face construction comprising a frame member at the upper extremity of said desk, a top member providing a normal area of working surface on 150

5 said desk and mounted upon said frame member so as to permit relative forward and rearward movement with respect to said frame member, a relatively low upstanding sheet metal strip along the rear side of said desk providing a guard rail for the desk surface and a stop for determining the rearmost position of said movable top member, a second top member pivoted along its rearward edge at said rail to swing between a horizontal position and a vertical position, means associated with said movable top member for aligning the upper surface thereof in the same plane with that of the pivoted member whenever the latter is in its horizontal position, and means for limiting the forward movement of said movable top member at that position just sufficient to provide a space for accommodating said pivoted member in a horizontal position for providing an extended continuous area of working surface on said desk.

10 6. In a desk top of the class described, a sliding top member, a pivoted top member, means for mounting said members on a desk, a flange member carried by said sliding member, and means for limiting the movement of said sliding member in one direction whereby the flange member co-acts with the pivoted member to align the upper surface thereof in the same plane with that of the sliding member for providing an enlarged continuous surface portion.

15 7. In furniture top construction, a sliding top member and a pivoted top member, a rearwardly extending flange on the rear of said sliding member for cooperating with the free end of the pivoted member to align the upper surface thereof in the same plane with that of the sliding member for providing a continuous extended area of working surface, and a forwardly extending bracket secured to the rear of said sliding member for limiting its movement in one direction and for locking it in extended position.

20 8. In furniture top construction, a sliding top

member providing a normal area of working surface on said desk, a pivoted top member adjustable for providing an additional area of working surface on said desk in the same plane as the surface of said sliding top member, and means comprising a flange member disposed along one edge of said sliding top member supportably engaging the movable edge of said pivoted member along its length for aligning the surfaces of said members on their contiguous edges to provide an enlarged continuous area of working surface on said desk in the same plane.

25 9. In furniture top construction, a sliding top member and a pivoted top member, a rearwardly extending flange on the rear of said sliding member for cooperating with the movable end of the pivoted member to align the upper surface thereof with that of said sliding member for providing a continuous enlarged area of working surface in the same plane, and means for limiting the forward movement of said sliding member at that position just sufficient to provide a space for accommodating said pivoted member in a horizontal position.

30 10. In a desk of the class described an articulated working top surface comprising a sliding surface member and a folding surface member, said folding surface member comprising a plurality of hinged leaves one of which is pivotally secured at the back of said desk and the other of which is pivotally secured to the rear edge of said sliding surface member, said sliding surface member being forwardly movable to position the leaves of said folding surface member in a horizontal plane to provide an enlarged continuous area of working surface and said sliding surface member being rearwardly movable to fold said leaves bellows-like or zig-zag into a substantially vertical plane at the rear of said desk.
